UNITED STATES PATENT OFFICE.

CHARLES HERBERT SCOTT, OF GLOUCESTER, ENGLAND.

APPARATUS FOR THE MANUFACTURE OF INLAID LINOLEUM.

1,173,875.

Specification of Letters Patent. Patented Feb. 29, 1916.

Application filed November 28, 1914. Serial No. 874,513.

To all whom it may concern:

Be it known that I, CHARLES HERBERT SCOTT, a subject of the King of Great Britain, residing in Gloucester, England, have invented certain new and useful Improvements in Apparatus for the Manufacture of Inlaid Linoleum, of which the following is a specification.

This invention relates to improvements in so-called flat apparatus for the manufacture of inlaid linoleum in which tesserae of the required shape and size are cut or stamped from sheets of previously rolled self-color linoleum and deposited on the canvas backing in the positions and order required in the finished linoleum, being afterward consolidated in a suitable press.

In machines of this type as previously made, the sheets of self-color linoleum are cut through dies over the canvas which forms the backing and are deposited on to this canvas, which has an intermittent motion, the operation being completed after the canvas has passed under successive dies one or more for each color employed in the finished linoleum. Such machines have considerable disadvantages. For instance the fact that the self-color linoleum sheets must be placed in position over the canvas and the waste be afterward removed from over it causes great trouble, as any pieces of debris or bits which may accidentally fall, fall on the finished or partially finished goods and spoil the pattern, and in operation the arrangement or construction of the machine obstructs a view of the linoleum as it is built up, which gives rise to considerable trouble. It is also often impossible to make more than a small portion of the pattern of one color with one die plate, as if a considerable portion of the plate is cut away it becomes too weak. It is also very difficult to change the patterns and to set new ones, as all this work has to be done on the top of the table in an inaccessible position.

The object of the present invention is to provide a machine which shall obviate these and other disadvantages of machines as at present constructed and at the same time

a machine which shall operate more quickly and have a larger output of linoleum.

The invention consists essentially in apparatus in which the tesserae of the different colors are cut or stamped out in a separate punching or cutting machine in which they are inserted into a combined spacing and die plate adapted to be subsequently moved into position over the canvas backing where they are deposited still in correct position on to the canvas and further in means for bringing the spacing and die plate into register in both the punching or cutting and in the depositing sections of the machine.

The invention will be fully described with reference to the accompanying drawings, in which one embodiment of the invention is illustrated.

Figures 1 and 1^a combined is a sectional plan view of the machine. Figs. 2 and 2^a combined is a sectional side view of the machine taken on line 2—2 of Figs. 1 and 1^a. Fig. 3 is a section on line 3—3 of Fig. 1. Fig. 4 is a section on a larger scale through the punch or cutter. Fig. 4^a is a detail thereof. Fig. 5 is a section through the essential part of a depositing section of the machine. Figs. 5^a, 6, 7, 8 and 9 show various details of the apparatus.

Referring to Figs. 1 and 1^a of the drawings the apparatus comprises a series of punches or cutters A and a corresponding number of depositing or dabbing sections B. The number of these punches and dabbers corresponds to the number of colors to be employed in the finished pattern, but it will of course be understood that a machine having a greater number of such sections than the colors required may be employed to produce linoleum, the sections in excess of such number in such a case not being used.

The punches A are arranged in line beside one another as near together as possible while allowing freedom of access and the dabbers B are correspondingly arranged in line beside one another, the lines of punches and dabbers being in their turn arranged as near together as possible.

Underneath, or rather through the dabbers, passes an endless band or table F of

any suitable construction carried by the wheels or drums C at either end of the machine to which intermittent movement is given by the pawl c and ratchet c' from the eccentric D mounted on the shaft d driven through the bevel wheels e', e from the main driving shaft E of the machine. The wheels or drums C are preferably provided with teeth adapted to engage corresponding teeth f (see Figs. 5 and 5^a) or recesses on or in the endless band or table F to insure that it is moved forward positively without any slip. The endless band or table F is preferably formed of steel slats f' and is adapted to support and carry the canvas G forming the backing for the linoleum through the machine. To prevent the canvas G slipping during its passage through the machine and also to retain the tesserae of linoleum in place after they have been dabbed down until the pattern is filled up the slats f' are provided with short upwardly extending pins H of such a length as will not penetrate right through the linoleum.

25 An extra press J is preferably provided, at the end of the machine, to give a final consolidating pressure to the linoleum, before it is removed from the endless band.

The punch A comprises a stationary upper bed or platen a' and a lower upwardly acting punch or cutter table a between which the sheet K of self-color linoleum is intermittently fed laterally in the manner hereinafter to be described. Between the platen a' and the punch a are arranged two plates having perforations in them corresponding in size and position to the size and position of the tesserae of that color desired in the pattern of the linoleum being made. The self-color linoleum passes between these two plates which are pressed tightly against it on either side during the punching operation and thus assist in producing a clean cut and in preventing fracture or crumbling of the linoleum on cutting. The upper of these plates L forms the die and positioning plate and is mounted in such a way as described below that it may be traversed backward and forward between the punch A and its corresponding dabber B. The lower plate M forms a guide plate and is preferably so mounted that it normally stands flush with the faces of the actual tesserae punches N. For this purpose the plate M is supported on springs m carried on the punch table a which always tend to push the plate M up to the faces of the punches N. After each punching operation the punches N are left normally projecting through the sheet K of self color linoleum, but the plate M under the action of the spring m pushes this linoleum debris upward of the punches N and thus frees them for the next operation.

65 Where a machine is to be used continually on a standard pattern the punches N may be

mounted directly on the punch table a, but where the pattern is liable to be changed the punches N may be mounted on a separate punch plate n as shown in Fig. 4. To insure the register of the punches N with the plates L and M one of these plates, which are preferably made at the same time so as to insure their agreement, is laid on the punch plate n and the punches N are inserted through the corresponding perforations in the plate L or M and secured in position before the perforated plate is removed. Further, to insure registration at each operation, in the machine the three plates n, M and L (or where no plate n is employed the plates M and L) are provided with two or more perforations outside the limits of the pattern which are adapted to fit over register pins O on the punch table a. These pins O are preferably tapered throughout or at 85 their points. The plates n and M never leave the pins O as they rise and fall with the table a and as described below the plate L is supported in such a manner that it is free to move slightly on its carriage so that 90 as the pins O on the rising of the punch table enter the register holes therein it may be moved into exact register with the plate M and the punches N.

The table a may be raised and lowered to 95 punch or cut out the tesserae in any suitable manner. As shown each punch is operated by a pair of cams P operating together one mounted on the main driving shaft E and the other on a second shaft p driven from 100 the shaft E at the same speed. The cams P may be arranged as shown to give a considerable lift to the table a so that at the bottom of the stroke it may be well out of the way of the platen a' to facilitate manipulation and examination. As such a stroke is not however generally necessary the 105 whole of the cam face is not employed in normal working. To this end loose bars p' are provided adapted to be laid as shown upon the girders p² supporting the machine in such a manner that when the table a has been lowered sufficiently for normal operation it rests thereon as shown in Fig. 3. 110 When a pattern has to be changed or examination is necessary the bars p' are removed and the table can be dropped right down. In normal operation therefore only the 115 summits of the cams P act on the table a, bowls or runners p³ being preferably provided on the underside thereof to take the thrust of the cams.

To insure the return or lowering of the table a a lever and link motion a⁴ operated by cams a⁵ on the shafts E and p may be 125 employed where desired. Guides a⁶ may also be provided to insure the correct movement of the table a.

The die and positioning plate L is preferably made of some thickness and the 130

punches N are made of such a length and throw that the tesserae Q of linoleum as they are cut out are pressed a little way upward into the perforations l in the die plate 5 and on the lowering of the punches N are retained in these perforations l by their own expansion or elasticity. Each of the perforations l is provided with a slide or piston l' which is preferably supported by 10 one or more springs l² so that it is held up in the plate L and does not drop through it. The platen a' is also preferably formed with recesses a² to receive the pistons l' when the plate is moved upward during the punching 15 operation and with ribs or stops a³ to support the plate and hold it while the actual cutting is taking place.

The plate L is slung or supported, somewhat loosely, as above described, from a 20 carriage adapted to transport it backward and forward between the punch A and the dabber B. This carriage and its transport device may be of any convenient construction. As shown the carriage consists of a 25 pair of slides R one on each side of the platen a' adapted to slide on bearers r carried by the frame of the machine. The slides R are provided with racks r' engaged by wheels r² mounted on the shaft r³ to 30 which reversible rotation is given by the quadrant r⁴ which is reciprocated by a lever and link motion r⁵ operated by a cam r⁶ on the main shaft E of the machine. The plate L is moved over from the punch carrying 35 the tesserae Q in their proper positions for the pattern into the approximately correct position under the dabber B and when in this position just before the dabber operates register pins o similar in shape to the pins O 40 on the punch operated by a lever and link motion o' from a cam o² on the shaft d are raised and, entering the same registering recesses as the pins O bring the plate into correct register over the moving table F 45 and the canvas G. When in this position the dabber B is lowered in any convenient manner and engaging the slides or pistons l' in its downward movement (see Fig. 5^a) pushes the tesserae Q down out of the 50 perforations l in the plate L on to the canvas G where it is held in position by the pins H. These pins are preferably so arranged that they enter the bottom of the tesserae just before they become entirely free from the 55 plate L. The dabber B may be operated in any suitable manner. As shown it is operated through a lever and link motion b from a cam b', on the shaft d. The carriage with the plate L is then returned to the punch 60 A, the endless table F is moved one step forward and the action is repeated.

Where in any pattern it is necessary to cut away much of the plate L this may be reinforced by a strengthening back plate l³ 65 in which case the slides or pistons l' may be

made with a center rod or shank l⁴ passing through the back plate l³, as shown in Fig. 7 so as to weaken the plate l³ as little as possible. In this case the supporting spring l² may be arranged spirally around the 70 shank.

The self-color linoleum K from which the tesserae are cut may be fed forward into the punch A in any suitable manner. A convenient arrangement is shown in Figs. 3, 4, 75 4^a, 8 and 9. In this arrangement endless reciprocating chains S carried on the wheels s, s arranged at both ends of the punching machine are adapted to move backward and forward a gripper T adapted to grip the 80 linoleum and feed it forward after each punching operation. For this purpose the wheels s are keyed upon the shaft s² which is periodically rotated in opposite directions by means of the wheel s³ which is driven by 85 suitable chain or other gear from the shaft r³ which receives reversible rotation from the quadrant r⁴. In this way it will be seen that simultaneous forward movement may be given to the plate L and the linoleum K 90 at the same time.

The gripper T comprises an upper cross plate t' and a lower cross plate t carried by brackets t² at either side of the punch supported by and adapted to slide on or in 95 grooves r¹ formed in the bearers r carrying the carriage for the plate L. The brackets t² are attached to the chains S so as to be movable or slidable therewith in the grooves r¹. The lower cross plate t is 100 formed with a recess in its under face in which is arranged a plate t³ having a number of upwardly projecting pins t⁴ secured therein which are adapted to pass through corresponding holes in the upper face of the cross plate t. The pin plate t³ is capable of being moved up and down in the recess in the plate t in such a manner that the pins t⁴ 105 may be sheathed in the plate t or project upwardly through it against the upper plate t', 110 and it is supported or slung at each end on a toggle lever t⁵ in such a manner that when the toggle lever t⁵ is in the dead center position the pins t⁴ are sheathed but when the lever t⁵ is not in that position the pins project, 115 and to insure such projection springs t⁶ are provided suitably arranged in such a manner as to press the pin plate t³ upward.

The linoleum K passes between the cross plates t, t' and it will be seen that when the 120 pins t⁴ are sheathed the gripper T can be moved without affecting the linoleum but when the pins project they enter the linoleum and any movement of the gripper carries the linoleum with it. Supposing now 125 that the gripper has gripped the linoleum and is moving it forward—the toggle lever being bent—it is necessary at the end of the forward stroke to release the linoleum from the gripper so that the latter may be moved 130

back to the starting point without taking the linoleum with it. This is accomplished by fitting suitable stops to engage the forwardly projected bent links of the toggle t^5 as it moves forward causing it to take or slightly pass the dead center position as it comes to rest thus releasing the linoleum from the pins. The gripper T can then be moved back to the starting position leaving the linoleum K in the position to which it has been moved forward. To cause the gripper on the other hand to seize the linoleum when it is to be moved forward the toggle t^5 is provided with a catch lever t^7 and the punch table a carries a spring latch t^8 adapted to rise and fall therewith in such a manner that in the upper position it engages the lever t^7 and as it is moved down again with the table a pulls the lever t^7 down with it till the toggle is over the dead center when the spring t^8 completes the motion and forces the pins into the linoleum ready for the next traverse. The gripper T is also preferably provided with a doctor U adapted to slide over the face of the plate M as the gripper moves forward to sweep off any loose debris or fragments of linoleum that may have fallen on to the plate. A similar doctor u (see Fig. 6) is fixed at the other end of the punch adapted to scrape the underside of the plate L as it moves forward to remove any particles adhering to the underside of said plate.

Upon the shaft s^2 are mounted wheels V having pins v adapted to engage the selvage of the linoleum and assist its forward movement. These wheels are preferably free to rotate on the shaft s^2 and are driven through a ratchet v' and pawl v^2 in such a manner that the wheels only rotate in the forward direction and remain stationary when the shaft s^2 rotates in the reverse direction. They are preferably connected by an angular sleeve v^3 upon which rests the free end of a hinged flap v^4 in such a manner that as the sleeve rotates it gives a jerking motion to the flap to shake off any fragments or debris of the linoleum that may fall or be pushed thereon by the doctor U. Such fragments with the punched sheet are fed downward to a cutter in known manner and return to be ground and remade up into linoleum.

A brush W (Fig. 6) for brushing the face of the plate L on either or both the forward and return motions may be employed and a lubricator X for known purposes may also be used.

Having thus described my invention and the best means I know of carrying the same into practical effect, I claim:—

1. Apparatus for the manufacture of inlaid linoleum comprising a punch adapted to simultaneously cut and space the tesserae of one or more repeats of one color in the

linoleum, a die plate coöperating with the punch adapted to receive the tesserae and maintain them properly spaced, means for transferring said die plate to the building up machine, and means for depositing the tesserae from said plate properly spaced upon the canvas backing. 70

2. Apparatus for the manufacture of inlaid linoleum comprising a flat punch plate, punches thereon corresponding in size and spacing to one or more repeats of the tesserae of one color in the linoleum, a die plate corresponding to and coöperating with said punch plate, means for operating the punch plate to simultaneously cut and deposit one or more repeats of such tesserae in said die plate, means for transferring said die plate to the building up machine, and means for depositing the tesserae from said die plate properly spaced upon the canvas backing. 75 80 85

3. Apparatus for the manufacture of inlaid linoleum comprising a punch adapted to cut and space the tesserae, transfer means adapted to receive the cut and spaced tesserae, means adapted to deposit the spaced tesserae upon the canvas backing and means for insuring registration of the punch, the transfer means and the canvas backing. 90

4. Apparatus for the manufacture of inlaid linoleum comprising a punch adapted to cut and space the tesserae, transfer means adapted to receive the cut and spaced tesserae, means adapted to deposit the spaced tesserae upon the canvas backing, means for insuring registration of the punch, the transfer means and the canvas backing. 95 100 105

5. Apparatus for the manufacture of inlaid linoleum comprising a flat punch plate, spaced punches thereon, a flat die plate corresponding to and coöperating therewith, spring urged plungers in the matrices of said die plate and means for operating said plungers to discharge the tesserae from the die plate and deposit them on the canvas backing. 110 115

6. Apparatus for the manufacture of linoleum comprising a punch adapted to cut and space the tesserae, transfer means adapted to receive the cut and spaced tesserae and deposit them upon the canvas backing, pins upon the punch, corresponding recesses on the die plate to receive said pins 120 and insure registration of the punch and die plate, and corresponding pins upon the building up machine adapted to enter the same recesses in the die plate to insure registration of the canvas backing and the 125 die plate.

7. Apparatus for the manufacture of linoleum comprising a punch adapted to cut and space the tesserae, transfer means adapted to receive the cut and spaced tes- 130

seræ and deposit them upon the canvas back-
ing, a gripper adapted to grip the linoleum
blank, means for moving said gripper for-
ward to feed the linoleum, means for re-
leasing the linoleum from the gripper and
means for returning the gripper to the
starting position.

In testimony whereof I have signed my
name to this specification in the presence of
two subscribing witnesses.
